UNITED STATES PATENT OFFICE.

EDWARD D. GALLAGHER, OF NEW YORK, N. Y., ASSIGNOR TO ANCELL H. BALL AND THOMAS A. BALL, A COPARTNERSHIP TRADING UNDER THE NAME OF BEST & COMPANY, OF NEW YORK, N. Y.

LAST.

1,141,326.

Specification of Letters Patent.

Patented June 1, 1915.

Application filed January 25, 1915. Serial No. 4,095.

To all whom it may concern:

Be it known that I, EDWARD D. GALLAGHER, a citizen of the United States, residing at New York, borough of Manhattan, county and State of New York, have invented certain new and useful Improvements in Lasts, of which the following is a clear, full, and exact description.

This invention relates to improvements in lasts upon which shoes are molded and made, and one of the objects of the present invention is to provide a last of such construction as to enable the formation thereon of an improved shoe as shown in a copending application Serial No. 4096 filed by me on even date herewith.

Other objects of the invention are to provide a practical and efficient last.

These being among the objects of the present invention, the same consists of certain features of construction to be herein-after described and then claimed with reference to the accompanying drawings illustrating a suitable embodiment of the invention in which—

Figure 1 is a side elevation of a last for a left shoe; Fig. 2 is an underside view thereof; Fig. 3 is a transverse outline section on the line 3—3 Fig. 2, said view showing at X in dotted lines the outline of a forward cross section of said last on the line X—X Fig. 2; Fig. 4 is a transverse section in outline on the line 5—5 Fig. 2, indicating in dotted lines at Y the outline of the forward cross section at Fig. 3; Fig. 5 is a transverse section on the line 5—5 Fig. 2 in the direction of the arrow, showing the rearward parts in elevation and the outline of the heel in dotted lines; and Fig. 6 is a cross section on the line 6—6 Fig. 2 in outline, partly broken away, and indicating in dotted lines a forward section corresponding with the cross section in Fig. 4.

The last illustrated is provided with a heel 10, a waist 11 and forepart 12, and the inner longitudinal side portion of the waist 11 is abnormally curved inwardly as at 13.

The longitudinal axis of the heel and waist at the bottom of the last and the longitudinal axis of the forepart are so disposed that they will lie at an angle to each other, and if a line 14 be drawn longitudinally of the bottom of the last so as to divide a line 15 extending transversely across the inner portion of the forepart 12 and the trans-

verse inner portion 16 of the heel 10, the curve of the side portion 13 of the waist will lie quite close to the said line 14. On a line drawn transversely across the narrowest portion of the bottom of the waist 11, the degree of separation between the curve 13 and the said line 14 will be comparatively slight. The transverse line 17 across the narrowest part of the waist 11 is therefore considerably offset relatively to the said line 14. Above the narrow waist portion at 17 it will be seen that the width of said waist is at 18 greater than the underlying portion and lies approximately equally on both sides of said line or axis 14.

Just to one side of but preferably slightly back of the point 19 corresponding with the big toe joint, the under surface of the last has a reverse arch, depression or concavity 20 which enables the formation of an arch or convexity in the metatarsal region of the shoe. The said depression or concavity 20 is indicated in Fig. 2 in outline, and as shown it extends as far as the incurve of the side portion 13. Just outside of the indicated outline of said depression or concavity 20 the under surface of the last is raised so that the depression or concavity 20 occupies a relatively small area.

The undersurface of the last is substantially even at the forepart and the heel part thereof and between points to one side of approximately one-half of the width of the waist of the last, except that it is concaved or depressed to one side of and directly behind the location for the big toe joint so that said concavity or depression is intersected by an approximately central longitudinal line at said surface, said concavity or depression having dimensions approximately one-half the width of said surface and, transversely, substantially the same measurement at least as said width, and being coincident with the location of the metatarsal bones of the human foot as before stated.

The inset and curved portion 13 of the last enables an arched platform to be produced at the inner side of the shoe, above the sole, while the substantially straight inside line at 21 and the broad curving outside line at 22 enables the shoe to be formed with a forepart to provide ample room for the toes. The described construction of the last enables a shoe to be produced with all of

the advantages which are set forth in my said copending application. The outline and the shape of the last substantially correspond with the lines of a normally sound foot as it leaves its mark on the sand.

What I claim is:—

1. A shoe last comprising a body having its entire under-surface substantially even except that it is concaved or depressed with-
10 in an area which is relatively small as com-
pared with the area of said substantially even surface, at a location to one side of
and directly behind that corresponding with
the big toe joint so as to be intersected by
15 an approximately central longitudinal line
at said surface, said concavity or depression
having dimensions approximately one-half
the width of said surface and, transversely,
substantially the same measurement at least
20 as said width, and being coincident with the
location of the metatarsal bones of the hu-
man foot.
2. A shoe last, comprising a forepart and
a heel part, and having a waist with its in-
25 ner longitudinal side portion curved abnor-
mally inwardly toward an imaginary
straight line which equally divides those
transverse portions of the heel part and
forepart which are directly contiguous to
30 the end portions of said waist, the degree
of separation between said curve and imagi-
nary line corresponding approximately

with one third or less of the distance across
the narrowest part of the bottom of said
waist, the under-surface of which last is 35
concaved or depressed at a location which is
coincident with the location of the meta-
tarsal bones of the human foot.

3. A shoe last, comprising a forepart and
a heel part, and having a waist with its in-
40 ner longitudinal side portion curved abnor-
mally inwardly toward an imaginary
straight line which equally divides those
transverse portions of the heel part and
forepart which are directly contiguous to
45 the end portions of said waist, the degree of
separation between said curve and imagi-
nary line corresponding approximately with
one-third or less of the distance across the
narrowest part of the bottom of said waist,
50 while above the said bottom the width of
the said waist is greater and lies approxi-
mately equally to both sides of said line,
the under-surface of which last is concaved
or depressed at a location which is coinci-
55 dent with the location of the metatarsal
bones of the human foot.

Signed at New York, N. Y., this 23rd
day of January 1915.

EDWARD D. GALLAGHER.
